UNITED STATES PATENT OFFICE.

UGO PAVESI AND GIULIO TOLOTTI, OF MILAN, ITALY, ASSIGNEES, BY MESNE ASSIGNMENTS, TO THE P. T. WHEEL COMPANY, OF DAYTON, OHIO, A CORPORATION OF OHIO.

TRACTOR.

1,298,781.

Specification of Letters Patent.

Patented Apr. 1, 1919.

Application filed October 29, 1915. Serial No. 58,726.

To all whom it may concern:

Be it known that we, UGO PAVESI and GIULIO TOLOTTI, both subjects of the King of Italy, the post-office address of both being 18 5 Oglio street, Milan, Italy, have invented new and useful Improvements in Tractors, of which the following is a specification.

This invention relates to a tractor such as employed for drawing very heavy loads 10 where it is necessary that the wheel shall have a very good tractive effect upon the ground. It has been attempted heretofore to produce such a wheel by attaching to the wheel rim a plurality of shoes which engage 15 the ground as the wheel rotates and these shoes have usually been provided with means for digging into the ground to give a purchase or reaction point upon which the wheel can exert its tractive effort.

20 A principal object of the invention is to produce a tractor which will give substantially the same effect as though the wheel were rolling upon a track.

Another object of the present invention is 25 to produce a tractor having bearing members supported by a wheel in such a way that as the wheel advances it places the bearing members in succession upon the ground and then rolls across each bearing member 30 in succession.

A further object of the invention is to provide means for preventing the wheel from slipping on each bearing member as it rolls across it.

35 A further object of the invention is to provide a tractor-wheel carrying bearing members or shoes and having improved means for supporting and guiding the bearing members upon the wheel so that when 40 the wheel advances, it will maintain at least two of these bearing members upon the ground and the bearing members will then operate to support the wheel which rolls across their upper side with a true rolling 45 movement, and also to construct the bearing members so that in the rolling movement the wheel makes a mechanical engagement with them so that the bearing members constitute sections of a rack and the wheel operates as a gear rolling upon the rack. Thus 50 the wheel rolls uniformly and exerts a continuous uniform tractive effort.

Further objects of the invention will appear more fully hereinafter.

The invention consists in the general combination of parts and features to be described hereafter all of which contribute to produce an efficient tractor. 55

A preferred embodiment of the invention is described in the following specification, 60 while the broad scope of the invention is pointed out in the appended claims.

In the drawing—

Figure 1 is a side elevation and partial section of a tractor embodying our invention. 65

Fig. 2 is a vertical section taken through the lower portion of the tractor shown in Fig. 1 but showing a single bearing member in place so as to render the view more intelligible. 70

Fig. 3 is a diagrammatic side elevation illustrating another embodiment of the invention.

Fig. 4 is a view similar to Fig. 3 and showing still another embodiment of the invention. 75

Fig. 5 is a diagrammatic view to which we shall refer in describing the elemental or kinematic problem.

Fig. 6 is also a diagrammatic view and 80 illustrating one manner of laying out the profile of one of the bearing members or shoes.

The tractor preferably comprises a wheel 1 which may be of spider form. Upon this 85 wheel we mount a plurality of bearing members which are disposed along the rim of the wheel and we provide means for supporting and guiding the bearing members on the wheel so that when the wheel advances it 90 operates to lay the bearing members in succession upon the ground. The rim of the wheel is supported upon each bearing member in succession and moves forward by a rolling movement on each bearing member. 95 The bearing members are preferably bodily movable in and out in a radial direction on the wheel, and the tractor operates in such a way that there are constantly two of the bearing members on the ground under the 100 wheel and across which the wheel rolls. As soon as the wheel is supported on the foremost bearing member, which is on the ground, the rear bearing member is released and is preferably arranged to be pulled inwardly on the wheel. In this way we get substantially the same effect as though the wheel were rolling along on a continuous 105

track made up of members such as the bearing members.

In order to prevent any slipping under the rim of the wheel where it rolls upon the bearing members, and in this way to give a very effective and high tractive effort, we prefer to construct the bearing members and the wheel so that they have mechanical engaging means. This engaging means preferably operates so as to get substantially the same effect as a gear wheel rolling upon a continuous track. To this end, we prefer to form the wheel 1 with two separated rim members 2 and between them we mount the bearing members 3 which are supported on the wheel so as to be bodily movable on the rim and as the wheel rotates it lays these members in succession upon the ground, indicated by the line 4. The mechanical engaging means between the bearing members and the wheel is preferably constructed on a mechanical theory of construction for a rack and pinion or gear wheel. That is, we prefer to employ involute or cycloidal curves along which the engagement of the wheel and the bearing members occurs. This enables the wheel to exert a uniform tractive effort. According to our invention the mechanical construction may take a variety of forms to get the effect described above. By way of example, in Fig. 1, the bearing members 3 are mounted in the spaces between guide members or studs 5 which are placed equidistant along the rim of the wheel and which rigidly connect the rim members 2. Each bearing member 3 is preferably in the form of a shell-like block having a plate-like body 6, the forward and rear ends of which present shoulders 7 adapted to engage the ground and give a good hold or purchase upon it. In this embodiment of the invention, each bearing member substantially constitutes a single gear tooth of a rack which would coöperate mechanically with the studs 5 to transmit power to or from the wheel 1. The forward wall of each bearing member, that is, the wall which is disposed on the side toward which the wheel is moving, is provided with a curved profile or curved face 8 which curve is substantially an involute or cycloidal curve designed to coöperate with the stud so that it will maintain itself in engagement with the stud as the wheel rolls along over the bearing member. A similarly curved rear face 9 is formed on each bearing member which maintains contact with each stud 5 as it moves upwardly and away from the ground toward the rear side of the wheel. It should be noted that in the embodiment shown in Fig. 1 there is no pivotal or similar connection which attaches the bearing members to the wheel. Their connection to the wheel may be described as a "floating connection" and they are preferably simply at-

tached by springs 10 which pull them inwardly toward the middle portion of the wheel. These springs are preferably attached to each bearing member near its rear portion.

Near its side edges each bearing member or shoe is preferably formed with central and side webs 11 which connect the forward and rear walls of the bearing members and these side webs 11 preferably lie against and are guided by the inner faces of the rim members 2.

When the wheel is operating the rim members 2 roll on the upper sides of the plate portion 6 of the bearing members on substantially flat faces 12 (see Fig. 2) at which points the plate projects so as to give the effect of a flange at each side under the rim which supports the wheel independently of the mechanical engaging means. The studs 5 coöperating with the curved faces 8 and 9 prevent the rim members 2 from slipping on the shoes or bearing members at the points 12 and the curved faces 8 react against the studs so as to enable the wheel to exert a good tractive effort upon the bearing members.

We prefer to employ a sufficient number of bearing members to insure that at least two of them will constantly lie substantially flat on the ground under the wheel. As the wheel passes from the rearmost bearing member onto the one forward, the spring or springs 10 attached to the rearmost bearing member pulls it upwardly so as to hold it in place on the wheel as the wheel rotates. We prefer to form the underside of the plate bodies 6 of the shoes with depressions 13 which have the effect of increasing the biting power of the shoes on the ground. The springs 10 are sufficiently strong to prevent the forward ends of the bearing members on the forward side of the wheel from becoming dislodged. As the bearing members descend on the forward side of the wheel, the weight of each shoe exerts itself with a constantly increasing lever arm which results in slightly extending the springs, so that the bearing members swing outwardly slightly at their forward portions and so that they swing as though on a fulcrum about their heels or rear ends 14. In this way as the wheel rotates, it places the bearing members in succession substantially flatly upon the ground.

Under some circumstances, it may be desirable to employ means on the bearing members for penetrating the earth. If this is desired, we prefer to employ spade-like members such as the traverse plate 15 indicated in dotted lines in Fig. 1. If these plates are used they are simply attached in slots on the plate bodies 6 of the bearing members.

The principle of our invention may be ap-

plied to various kinds of construction and the embodiment described above is merely by way of example although we do consider it the preferred form of the invention.

5 As further examples of applications of the invention reference is had to Figs. 3 and 4 which show two other distinct embodiments. In the form shown in Fig. 3 the bearing members are in the form of simple plates 16

10 and while these plates constitute rack sections, the mechanical engagement between them and the wheel 17 is such as to employ a plurality of teeth instead of causing the shoe to operate as a single rack tooth. With

15 this arrangement the teeth 18 of the bearing member and the teeth 19 of the wheel mesh like an ordinary rack and gear wheel and these teeth keep the bearing members from shifting on the wheel. Near the rear portions

20 of the bearing members, springs 20 are attached which connect them with the wheel and pull them up into place on the wheel after the wheel has passed forward so as to roll onto the next bearing member. In this

25 embodiment of the invention, as in the form shown in Fig. 1, the wheel may be actually supported by the contact of its rim 17 with the upper face of the plate and the teeth merely prevent slipping.

30 The embodiment shown in Fig. 4 is in some respects the reverse of that shown in Fig. 1. That is, the bearing member 21 is formed with the two studs 22 which may carry rollers and between each pair of studs

35 a specially formed gear tooth 23 is provided on the rim of the wheel. The end of this gear tooth 23 conforms to the outline of the rim 24, so that the wheel rolls smoothly on the plate or bearing member 21 and 40 exerts a tractive effort upon the rollers at the involute or cycloidal faces 25. Although in Fig. 1 we have shown the studs 5 as plain studs, if desired, of course, these studs may be provided with rollers.

45 The general problem which presents itself to this invention may be illustrated by referring to Figs. 5 and 6. In Fig. 5 we may regard the plate 26 as a short section of a continuous track along which the wheel 27

50 is to roll. As the wheel proceeds, the point 28 on the wheel comes in contact with the point 29 at the rear edge of the plate 26. As the wheel rolls off the plate the point 30 of the plate contacts with the forward edge

55 of the plate at the point 31. The problem of the invention is not only to provide for this rolling effect but to prevent slipping of the rim of the wheel on this plate or bearing member.

60 In meeting the problem with a construction such as that illustrated in Fig. 1, the proper form for the forward and rear faces 8 and 9 of the bearing members may be plotted in the manner illustrated in Fig. 6.

65 Referring to this figure, 32 represents the

rim of the wheel which is supposed to be rolling upon the upper face 33 of the bearing member. The point 34 represents the center of the wheel which is directly over the point of tangency 35 between the wheel 70 and the bearing member. A succession of points, say for instance 10 points, may be laid off toward the right on a horizontal line 36. These points are numbered $a^1, a^2, \dots$ to a^{10} . With these points as a center, we 75 can locate the corresponding positions of the stud or roller 37. The locus of the roller when so located is indicated by a succession of short arcs $A^1, A^2, \dots$, corresponding to the points $a^1, a^2, \dots$, and if a curve 80 is drawn tangent to these arcs, $A^1, A^2, \dots$, it will give the proper outline or profile for the rear face of the bearing members. In a similar manner we may plot the curve for the forward face of the bearing members 85 through the medium of a plurality of short arcs $B^1, B^2, \dots$. Corresponding to the points $a^1, a^2, \dots$, we may lay off corresponding rim lines or arcs $c^1, c^2, c^3, \dots$, up to c^{10} .

90 In one aspect of the invention, the bearing members may be considered as constituting with the wheel a flexible rack which is continually passing under the wheel and upon which the wheel rolls.

95 What we claim is:

1. In a tractor, the combination, with a wheel, of a plurality of bearing members attached along the rim of the wheel, mechanical engaging means between said bearing members and said wheel, consisting of 100 guide members near the rim of the wheel and engaging faces on said bearing members, springs connecting said bearing members and said wheel and constructed to move an end of said members in a substantially radial direction on said wheel the opposite end having limited gravity movement and each of said members having a substantially flat face on which the rim 110 portions of said wheel ride.

2. In a tractor, the combination, with a wheel, of a plurality of bearing members attached along the rim of the wheel, each bearing member consisting of a shoe 115 constructed to engage the ground and having a curved forward face and a curved rear face so that each shoe constitutes an enlarged rack tooth, and springs holding said bearing members against said wheel and moving said members in a substantially radial direction on said wheel as said wheel rolls over said bearing members.

3. In a tractor, the combination of, a wheel having a plurality of rims, a plurality of bearing members disposed between said rims and bodily movable upon the wheel in and out in a substantially radial direction so that as the wheel advances it lays said bearing members in succession upon the ground, 125 130

springs attached to said wheel and to said bearing members, said wheel supported upon each bearing member in succession and moving forward by a rolling movement upon each bearing member, the rims of said wheel having engaging means for respectively engaging said members, said bearing member having curved faces extending between said rims and designed to maintain contact with said engaging means as the wheel rolls upon each bearing member and thereby preventing slipping of the wheel on each bearing member.

4. In a tractor, in combination, a wheel having two separated rim members, a plurality of equidistant engaging studs disposed in the space between said rim members, a plurality of shoes disposed respectively in the spaces between said studs, said shoes bodily movable in and out on the wheel in a substantially radial direction between said studs, springs attached to the wheel and exerting a tension on said shoes to pull the same inwardly on the wheel, said wheel and said shoes operating so that when the wheel advances it lays the shoes successively upon the ground and rolls across the upper side of each shoe in succession, each shoe having a curved forward face designed to maintain engagement with its corresponding engaging stud to prevent the rim of the wheel slipping on the shoe and coöperating with the stud as a rack tooth.

5. In a tractor, in combination, a wheel having two separated rim members, a plurality of equidistant engaging studs carried thereby in the space between said rim members, a plurality of shoes disposed respectively in the spaces between said studs and bodily movable on the wheel and coöperating with said wheel so that when the wheel advances it lays the shoes successively upon the ground and rolls across the upper side of each shoe in succession, each shoe having a curved forward face operating to maintain engagement with its corresponding engaging stud to prevent the rim of the wheel slipping on the shoe and coöperating with the stud as a rack tooth, and springs attached to said wheel and to the shoes respectively toward the rear part of each shoe, and exerting a tension on each shoe to pull each shoe inwardly on the wheel after the wheel has rolled over the same and operating to hold the shoes in place between the studs.

6. In a tractor, the combination of a wheel, a plurality of bearing members attached around the rim of the wheel, and bodily movable thereupon in and out in a substantially radial direction so that as the wheel advances it lays said bearing members in succession upon the ground to enable the wheel to move forward by a rolling movement upon each bearing member, each bearing member con-

sisting of a shoe constructed to rest upon the ground, having a curved forward face and a curved rear face so that each shoe constitutes a rack tooth, said wheel having means for engaging said curved faces, the said wheel operating as a gear wheel maintaining contact continuously with the faces of the shoe as a gear tooth when it rolls upon the shoe, each shoe having concave faces of substantially the same radius as the rim of the wheel adjacent the side edges thereof, said wheel having rim portions rolling on said faces and supporting the weight of the wheel independently of the said curved faces of said bearing members.

7. In a tractor, the combination of a wheel, a plurality of bearing members attached around the rim of the wheel, and movable thereupon so that when the wheel advances it lays said bearing members in succession upon the ground to enable the wheel to move forward by a rolling movement upon each bearing member, said wheel and said bearing members having engaging faces maintaining contact continuously with each other during the rolling movement of the wheel to prevent the wheel from slipping, and springs attached toward the rear ends of said bearing members with respect to the direction of rotation of the wheel for pulling the tractor members substantially radially inward on the wheel.

8. In a tractor, the combination, with a wheel, of a series of members carried on the rim of said wheel and having the shape of gear teeth, devices carried by said wheel between which said gear-tooth-shaped members ride, and springs holding said members in contact with said wheel rim and with said devices.

9. In a tractor, the combination, with a wheel, of a series of members carried on the rim of said wheel, but free to move bodily thereon and each acting as a gear tooth, devices fast on said wheel between which said members ride and against which the curved surfaces of said members roll, and springs holding said members on said wheel rim.

10. In a tractor, the combination, with a wheel, of a series of members carried on the rim of said wheel and over which said wheel moves, said members having curved forward and rear surfaces and acting as gear teeth, devices fast on said wheel adjacent said curved surfaces of said members, with which said curved surfaces coact, and means for yieldingly holding one end of said members in contact with said wheel rim and with said devices the opposite end being free to move by gravity within the limits determined by said devices.

11. In a tractor, the combination, with a wheel having oppositely disposed rims, of a series of members floating between guide

members on said rims and over which said wheel rolls, said members being bodily movable on said wheel and held in contact therewith solely by springs connected to said 5 wheel and said members, the opposite end being free to gravitate between limits determined by said guide members.

In testimony whereof we have hereunto set

our hands in the presence of two subscribing witnesses.
